UNITED STATES PATENT OFFICE.

THOMAS E. McNULTY, OF SAN FRANCISCO, CALIFORNIA.

CHAIR AND DESK ATTACHMENT.

1,291,975.

Specification of Letters Patent. Patented Jan. 21, 1919.

Application filed May 12, 1916. Serial No. 97,118.

To all whom it may concern:

Be it known that I, THOMAS E. McNULTY, a citizen of the United States, residing at San Francisco, in the county of San Francisco and State of California, have invented 5 certain new and useful Improvements in Chair and Desk Attachments, of which the following is a specification.

This invention relates to a detachable 10 chair or desk attachment, the object of the invention being to convert the ordinary chair or school desk back into one hygienic and anatomically correct.

While not limited to school or desk use 15 the invention is especially suited for use in correcting defects now found in the usual type of desk backs provided for use in public and private schools. A careful examination has disclosed the fact that by reason 20 of the present seating methods employed many pupils have contracted various spinal troubles that impair their health and also interfere with their studies, and which may in many cases account for the apparent back- 25 wardness of some pupils.

This difficulty usually comes from the use 30 of seats that are provided with a concaved shoulder panel of greater width than the shoulders of the pupil using it, and in some cases with a back higher than the top of the shoulders.

This would cause a pronounced case of 35 weak spine in time as the spine is not supported in the movements of the shoulder in the numerous positions that are required in the course of study.

Or the chair may be of the straight back 40 type with a distinct leanback so that when it supports the back of the pupil the weight of the body forces the hips and legs forward causing a diagonal strain on the spine, which curves in an outward position, causing 45 in time spinal and other troubles.

My invention is designed to correct these 45 objections without making it necessary to replace the present school furniture.

I have illustrated my invention as applied 50 to the back of a school desk of the ordinary construction, and in the drawings:

Figure 1 is a perspective view of a desk 55 with my attachment in position thereon.

Fig. 2 is a vertical section through the 60 desk back, my attachment being partly in

side elevation and in part in section, on the line 2-2 of Fig. 1. 55

Fig. 3 is a perspective view of a bracket.

Fig. 4 is a perspective view of a metal bar.

Fig. 5 is a section on the line 5-5 of Fig. 2. 60

In the drawings 1 represents a desk having a back 2.

A metal bracket 3, preferably though not necessarily in the form of a channel bar, has its upper end portion bent at a right 65 angle as at 4, and then bent downwardly as at 5. Midway or thereabout the bracket is formed with a slight obtuse angle 6, the upper portion extending slightly downwardly and forwardly, and the lower portion downwardly and slightly inwardly. The extreme lower portion is bent forwardly at 7 to conform to the usual slope of the lower portion of the desk or seat back.

Throughout its vertical portion the 75 bracket is provided with openings 8. Two of these brackets are provided and they are secured parallel to each other and a suitable distance apart, the bent end portions 5 and 7 being secured respectively to the seat or 80 chair back, at top and bottom.

Crosspieces 9, formed of wood, rounded on the top and bottom edges and of suitable width are channeled transversely on their rear faces as at 10, and set into said 85 channels are flat bars 11, their exposed faces being flush with the rear face of the crosspieces. These bars are of greater length than the width of the crosspieces and project above and below them. At their upper ends 90 they are provided with a hook member 12 in the shape of a cylindrical lug extending at an angle from the end of the bar. In the bars are also provided openings 13 through which securing devices in the form 95 of screws and bolts may be passed.

The pieces 9 are secured in place across the brackets 3 by engaging the lugs 12 of the bars 11 with proper openings 8 and are locked by bolts 15 which pass through other 100 openings 8 and through one of the openings 13 of each bar. Screws 14 are employed to secure the bars 11 to the crosspieces 9.

It will be noted that there is a slight difference in the cross sectional shape of the 105 crosspieces, the lower one being thinner at

the lower edge. This difference combined with the slight angle given the brackets at the point 6 gives a difference in inclination or slant to the crosspieces, favoring the correct shape and curvature of the spine.

In a correct sitting posture the body must have free movement in all members, and the attachments should be fitted to each desk to accommodate the pupil using it, so that he will have free shoulder and abdomen action.

The upper crosspiece should be set slightly below the shoulder blades, the lower across the pelvis, approximately at right angles with the thighs, and with the feet squarely on the floor the result will be square shoulders and erect chest position. The adjustability of the crosspieces with reference to each other is essential as there is a difference in length of curve of the spine in pupils of the same actual height.

I have illustrated a practical form of the invention but do not wish to be limited to the exact details of construction shown, or to the application of the device to a school desk or for the use of children only.

What I claim is:—

1. The combination with a desk back, having a seat in advance thereof, of parallel bars angled at their upper ends to space said bars from said back, and having an obtuse angle midway their ends, and per-

forated, cross pieces, bars secured to the cross pieces, and lugs carried by the last mentioned bars and adapted to engage the 35 perforations of the first mentioned bars.

2. The combination with a seat back, of brackets carried vertically thereby, said brackets having an obtuse angle intermediate their ends, and cross pieces detachably carried by said brackets and on opposite sides of said obtuse angle.

3. The combination with a desk back, of vertical brackets carried thereby, and having their body portions spaced from the back, 45 and detachable cross pieces carried by said brackets, said cross pieces being arranged at a slight angle to each other.

4. In a device of the kind described, fixed parallel vertical brackets having openings 50 therein, cross pieces, and bars secured to the cross pieces and projecting beyond their edges, said bars having lugs adapted to engage the openings in the brackets.

5. In a device of the kind described, 55 parallel vertical bars having perforations, cross pieces transversely grooved, bars secured to said cross pieces in said grooves, and lugs carried by the bars and adapted to engage the perforations of the first mentioned bars.

In testimony whereof I affix my signature.

THOMAS E. McNULTY.
